CLEAT FOR A SHOE

Munro M. Grant, % Ohio Athletic Specialty Co.,
113 Buckeye St., Elyria, Ohio

Filed June 1, 1961, Ser. No. 65,422

Term of patent 3½ years

(Cl. D7—5)

Fig. 1.

Fig. 2.

Fig. 3.

FIG. 1 is a top plan view of a cleat for a shoe, showing my new design;

FIG. 2 is a front perspective view of a cleat for a shoe, showing my new design; and

FIG. 3 is a side perspective view, the opposite side being substantially a mirror image thereof.

I claim:

The ornamental design for a cleat for a shoe, as shown and described.
